HARNESS FOR CROSS WEAVING

Filed June 19, 1935

Inventor:

Hugh H. Wood,

C. Wobensmith
Attorney.

UNITED STATES PATENT OFFICE

2,033,800

HARNESS FOR CROSS WEAVING

Hugh H. Wood, Westminster, S. C., assignor to
Steel Heddle Manufacturing Company, Philadelphia, Pa., a corporation of Pennsylvania

Application June 19, 1935, Serial No. 27,306

7 Claims. (Cl. 139—52)

This invention relates to loom harness for use in that method of weaving known as cross weaving (sometimes called leno, doup, or gauze weaving), in which the warp threads, arranged in pairs, are crossed or twisted about each other for successive picks, whereby the weft is bound more firmly than in plain weaves.

The principal object of the present invention is to provide metallic harness for cross weaving which will be simple, durable, and efficient, and which is so constructed and arranged as to eliminate the necessity for the jumper harness and the slackener mechanism which are commonly used in connection with metallic harness for cross weaving.

A further object of the invention is to provide loom harness of the character aforesaid in which crowding will be minimized, thereby to provide greater freedom in the shedding.

A further object of the invention is to provide loom harness of the character aforesaid, in the use of which the shedding mechanism may be simplified.

The nature and characteristic features of the invention will be more readily understood from the following description, taken in connection with the accompanying drawing forming part hereof, in which:

Figure 1 is an elevational view of a set of heddles and doup needles for controlling a pair of warp ends which are to be twisted about each other at successive picks during the formation of the weave, the same embodying the main features of the present invention;

Fig. 2 is an enlarged elevational view of the central portion of the structure shown in Fig. 1, the parts being shown in positions assumed in the formation of a shed;

Fig. 3 is a view similar to Fig. 2, showing the parts in the positions assumed at a succeeding pick; and

Fig. 4 is a side elevational view of the central portion of one of the standard or control heddles.

It will, of course, be understood that the description and drawing herein contained are illustrative merely, and that various modifications and changes may be made in the structure disclosed without departing from the spirit of the invention.

In carrying out the present invention, two doup needles 10 and 11 are employed, which are preferably of the form shown in the Kaufmann Patent No. 1,037,151, dated August 27, 1912, and are preferably made by punching or stamping from a thin flat strip of metal.

Each of said doup needles has at one end thereof an eye portion 12, in which the eye 13 for control of a warp end is located. The outer margin 14 of the eye portion 12 of each doup needle is arched or curved, while the inner margin 15 of said eye portion is preferably flat.

Extending from the eye portion 12 of each doup needle are two legs 16 which terminate in enlarged portions 17, each of which is provided with a slot 18 for connection of the doup needle with the means for holding the eye portions of the doup needles in engagement with the eye portions of the control heddles, which may be of any of the forms which are common and well known in the art.

There are provided three standard or control heddles, 20, 21, and 22. The two outer heddles 20 and 21 may be of identical conformation, one, however, being turned end for end with respect to the other. The standard or control heddles 20 and 21 are made of thin flat metal or wire, each of said heddles having an angularly extending portion 23, whereby the part 24 at one end of the eye portion of the heddle is offset laterally with respect to the part 25 at the other end thereof, to afford freedom of action of the doup needle as well as of the warp when the shedding occurs.

The central strip 26 of the eye portion of each of the outer standard or control heddles 20 and 21 is punched and pressed out of the main plane of the heddle (see Fig. 4), thereby permitting the eye portion 12 of the doup needle 11 to be disposed in the eye provided between said punched out strip 26 and the side strips 27, without distorting said doup needle, which, as hereinbefore set forth, is also preferably punched from thin flat metal. The side strips 27 are also preferably pressed out of the main plane of the heddle, as shown in Fig. 4.

The central portion of the middle standard or control heddle 22 is formed in a like manner to that of the outer standard or control heddles 20 and 21, also having an angularly extending portion 33, whereby the upper part 34 of said heddle 45 is offset laterally with respect to the lower part 35 thereof. Likewise, the eye portion of said middle heddle 22 has a central strip 36 punched and pressed out of the main plane of the heddle, thereby permitting the eye portion 12 of each 50 of the doup needles 10 and 11 to be disposed in the eye provided between said punched out strip 36 and the side strips 37 of said heddle, without distorting the doup needle.

The central strip 26 and the side strips 27 of 55

each of the outer standard or control heddles 20 and 21, as well as the central strip 36 and the side strips 37 of the middle standard or control heddle 22, follow the contour of the bend or offset in the respective eye portions of said heddles. These strips ordinarily extend from points in the straight portions of the respective heddles beyond the bend or offset at each end thereof.

The standard or control heddles may be mounted, by means of the heddle rod eyes 40 provided in the ends thereof, in harness frames (not shown) of the type commonly employed for the mounting of heddles for plain weaving, and the shedding mechanism employed may be of a very simple character. It should be noted that the outer heddles 20 and 21 are ordinarily operated in unison, the same being raised together when the middle heddle 22 is lowered, and being lowered together when the middle heddle 22 is elevated.

Hence it will be seen that a simple shedding mechanism may be employed in connection with the harness. It should be understood, however, that the doup needles 10 and 11 are preferably under spring tension or otherwise actuated so that the eye portions 12 of the same will at all times be held retracted against the end portion of the eye of one of the standard or control heddles.

In Fig. 1 of the drawing, the parts are shown in what might be termed a neutral position, the same illustrating a transitional stage in the manipulation of the warp ends.

When a shed is formed, the warp end A is always elevated, and the warp end B is always lowered. It will be noted, however, that the doup needle 11 for controlling the warp end A may be alternatively raised, either by the outer standard or control heddle 21 as shown in Fig. 2, or by the middle standard or control heddle 22 as shown in Fig. 3.

Likewise the doup needle 10, by means of which the warp end B is controlled, is always lowered, either by the middle standard or control heddle 22 as shown in Fig. 2, or by the outer standard or control heddle 20 as shown in Fig. 3.

It will be noted that, by the arrangement of the present invention, the utmost freedom of the warp will be obtained and crowding in the harness will be greatly minimized, there will be no likelihood of fouling of the respective warp ends, and shedding mechanism of a simple character may be employed.

I claim:

1. In harness for cross weaving, a set of harness members for controlling a pair of warp ends comprising a pair of doup needles each having an eye portion through which a warp end extends, a control heddle engaging one of said doup needles, another control heddle engaging the other of said doup needles, and a third control heddle engaging both of said doup needles.

2. In harness for cross weaving, a set of harness members for controlling a pair of warp ends comprising a pair of doup needles each having an eye portion through which a warp end extends, a control heddle engaging one of said doup needles, another control heddle engaging the other of said doup needles, and a third control heddle engaging both of said doup needles, each of said control heddles having an eye portion through which portions of a doup needle extend.

3. In harness for cross weaving, a set of harness members for controlling a pair of warp ends comprising a pair of doup needles each having an eye portion through which a warp end extends, a control heddle engaging one of said doup needles, another control heddle engaging the other of said doup needles, and a third control heddle engaging both of said doup needles, each of said control heddles having an eye portion through which portions of a doup needle extend.

prising a pair of doup needles each having an eye portion through which a warp end extends, a control heddle engaging one of said doup needles, another control heddle engaging the other of said doup needles, and a third control heddle engaging both of said doup needles, each of said control heddles having an eye portion through which portions of a doup needle extend, said eye portion having an angularly extending portion whereby the part at one end of the eye portion of the heddle is offset laterally with respect to the part at the other end thereof.

4. In harness for cross weaving, a set of harness members for controlling a pair of warp ends comprising a pair of doup needles made from thin flat metal each having an eye portion through which a warp end extends, a control heddle engaging one of said doup needles, another control heddle engaging the other of said doup needles, and a third control heddle engaging both of said doup needles, each of said control heddles being made of thin flat metal and having an eye portion through which portions of a doup needle extend, said eye portion having an angularly extending portion whereby the part at one end of the eye portion of the heddle is offset laterally with respect to the part at the other end thereof.

5. In harness for cross weaving, a set of harness members for controlling a pair of warp ends comprising a pair of doup needles made of thin flat metal each having an eye portion through which a warp end extends, a control heddle engaging one of said doup needles, another control heddle engaging the other of said doup needles, and a third control heddle engaging both of said doup needles, each of said control heddles being made of thin flat metal and having an eye portion through which portions of a doup needle extend, said eye portion comprising a central strip and two side strips.

6. In harness for cross weaving, a set of harness members for controlling a pair of warp ends comprising a pair of doup needles made of thin flat metal each having an eye portion through which a warp end extends, a control heddle engaging one of said doup needles, another control heddle engaging the other of said doup needles, and a third control heddle engaging both of said doup needles, each of said control heddles being made of thin flat metal and having an eye portion through which portions of a doup needle extend, said eye portion comprising a central strip and two side strips, said strips being punched and pressed out of the main plane of the heddle.

7. In harness for cross weaving, a set of harness members for controlling a pair of warp ends comprising a pair of doup needles made of thin flat metal each having an eye portion through which a warp end extends, a control heddle engaging one of said doup needles, another control heddle engaging the other of said doup needles, and a third control heddle engaging both of said doup needles, each of said control heddles being made of thin flat metal and having an eye portion through which portions of a doup needle extend, said eye portion having an angularly extending portion whereby the part at one end of the eye portion of the heddle is offset laterally with respect to the part at the other end thereof, and said eye portion comprising a central strip and two side strips, said strips being punched and pressed out of the main plane of the heddle.

HUGH H. WOOD.
